COIN COLLECTING MECHANISM BASE

George A. Long, Hartford, Conn., assignor to The Gray Telephone Pay Station Company, Hartford, Conn., a corporation of Connecticut

Application May 13, 1933, Serial No. 670,927

5 Claims. (Cl. 179—146)

My invention relates to the class of devices employed for supporting the coils used in collecting tolls for the use of telephone instruments, and an object of my invention, among others, 5 is to provide a base which shall form a particularly rigid support for the coils.

One form of my improved device and the process for making the same and in the practice of which the objects herein set out, as well as 10 others, may be attained is illustrated in the accompanying drawing, in which—

Figure 1 is a view of a sheet metal blank cut to proper form for producing my improved telephone mechanism base.

15 Figure 2 illustrates the formation of said blank in the first step of the process.

Figure 3 is a view of the blank resulting from this first step.

Figure 4 illustrates the second step in the process, the blank being cut in cross section.

Figure 5 is a view illustrating the shape of the blank resulting from this second step.

Figure 6 is a view of the blank obtained by a third step in the process, and

25 Figure 7 is a view in section through the dies illustrating the operation of this third step in the process.

Figure 8 illustrates the shape of the blank obtained by the fourth step in the process, and

30 Figure 9 is a view in section through said blank disclosing its shape as obtained by this fourth step.

Figure 10 is a plan view of the finished blank, and

35 Figure 11 is a view illustrating the manner of supporting coils upon my improved base.

Telephone toll collecting apparatus in common use at the present time embodies electric coils that are used for manipulating the coin collecting mechanism, said coils being supported upon a dish shaped base depending within the top of the coin collection box on the front of the instrument. It is required that said coils shall be very rigidly supported as, if they are moved 45 on their supports after being set up and adjusted, their operation becomes faulty if not useless. In the use of the bases heretofore employed this fault has been found to exist to a considerable extent, the rough usage in the 50 transportation of the instruments often displacing the coils to a greater or lesser extent and thereby rendering them ineffective. By the use of my improved base herein illustrated and described a very rigid and stable support for the 55 coils is provided such that the instruments are

capable of withstanding jars and shocks to a degree to maintain the coils rigidly in position after they have once been adjusted and fixed in place.

In the accompanying drawing the numeral 12 5 denotes a blank cut from sheet metal with curved edges 13 and 14 and tapered ends 15 joined with the curved edges 13 by rounding corners 16. In the first operation this blank is subjected to the action of a punch 17 which forces the blank 10 into a die 18 against a pressure pad 19, the punch operating through a pressure ring 20, as shown in Fig. 2 of the drawing. This produces a dish-shaped blank having a concaved bottom 21 and inclined lips 22 around three sides, the side 23 15 being open.

In this first operation the pad 19 has lugs 24 on opposite sides which start the formation of supporting bosses 25 within the dish-shaped structure and near one end thereof, and as shown 20 in Fig. 3, said lugs being spaced from the end wall 26, it being noted that the curved edges 13 and 14 and the tapered ends 15 have disappeared together with the rounded corners 16, the whole structure now being of substantially rectangular 25 shape.

In the next step herein shown in the process the depression 21 in the bottom is straightened, forming a flat bottom 27, as shown in Fig. 4 of the drawing. This concaved bottom is for the 30 purpose of supplying metal to impart angularity to the corners 28 and increased angularity is also given to the supporting bosses 29, and as shown in Fig. 4. The tapered form of the lips 22 is maintained in this second step in the process. 35

In the next and third step herein shown in the process the lips 30 are formed substantially at right angles to the sides of the dish-shaped structures and a little greater angularity is given to the supporting bosses 29, a punch 31, die 40 40 32, pressure pad 33 and pressure ring 34 being employed in this operation.

In the last step herein shown in the process the dish-shaped structure assumes final form, as 45 shown in Figs. 9 and 10, the general structure being much the same as after the third drawing operation, simply a greater degree of angularity being given to the lips 30 and sides as compared with the bottoms and the supporting bosses 29. Certain holes, openings, indentations, etc. are 50 formed in the structure in this final operation and which do not require specific mention herein.

In use the lips 30 of the structure rest upon the top edge of the box for receiving the coin 55 and having the coin return chute therein of a

coin collecting telephone system in a manner that will be readily understood, and for which reason more specific illustration and description are omitted herein. A coil supporting bar 36 is 5 firmly secured to the tops of the bosses 29, bridging the space between them, and coils 37 acting to control movements of coin directing devices are secured to said bar.

It will be noted that in all of these operations 10 the bosses have included three sides only, that is, they are closed on all sides within the dish-shaped structure. This comprises an important feature of my invention as a very stable and rigid support for the bar 36 and hence the coils 37 is 15 provided sufficient to rigidly maintain the coils in position and effectually resist movement of the coils on the support by reason of jars, jolts or other abnormal causes.

I claim:

- 20 1. A sheet metal supporting plate for telephone mechanism, said plate comprising a bottom and sides located at an angle to said bottom, said plate including a supporting boss of substantially rectangular shape in cross-section rising from the 25 plate at the angle between said bottom and sides and with relatively angularly disposed supporting sides extending from the top of the boss to the plate on more than two sides thereof.
2. A sheet metal supporting plate for telephone 30 mechanism, said plate comprising a bottom and sides located at an angle to said bottom, said plate including bosses of substantially rectangular shape in cross-section arranged at opposite sides of the plate at the angle between said bottom and 35 sides and rising therefrom, and with relatively angularly disposed supporting sides extending

from the top of each boss to the plate on more than two sides thereof.

3. A sheet metal supporting plate for telephone mechanism, said plate comprising a bottom and sides located at an angle to said bottom, said plate including a boss of substantially rectangular shape in cross-section rising from the plate at the angle between said bottom and sides and with relatively angularly disposed supporting sides extending from the top of the boss to the plate, said 5 sides being continuous and unbroken from one boundary around the top to the opposite boundary of said sides.

4. A sheet metal supporting plate for telephone mechanism, said plate including a dish-shaped structure with oppositely arranged side walls, and bosses of substantially angular shape in cross-section located at the angle between the side walls and plate at opposite edges of the latter, said 10 bosses each including a top with relatively angularly disposed supporting sides extending from the top to said plate on all sides within said side walls which form sides of said bosses.

5. A sheet metal supporting plate for telephone mechanism, said plate including side walls arranged at an angle to the plate and bosses of substantially angular shape in cross-section located against said plate and side walls at opposite edges of the plate, each boss including a top and relatively angularly disposed supporting sides extending from the top to said plate on all 15 sides within said side walls and united at said top with said side wall, and a supporting bar bridging the interval between said bosses.

35

GEORGE A. LONG.
